(57) **CLAIM**

The ornamental design for a backpack with segmented shell, as shown and described.

DESCRIPTION

FIG. 1 is a top, front, left side perspective view of the backpack with segmented shell showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof, with the shoulder straps removed for ease of illustration; and,

FIG. 7 is a bottom plan view thereof.

The cross-hatched lines shown in the drawings represent a textured, fabric surface.
